UNITED STATES PATENT OFFICE.

GEORGE W. STICKLE, OF ST. ALBANS, VERMONT.

CARPET-HOLDING FRAME.

No. 833,901.

Specification of Letters Patent.

Patented Oct. 23, 1906.

Application filed December 4, 1905. Serial No. 290,303.

To all whom it may concern:

Be it known that I, GEORGE W. STICKLE, a citizen of the United States, residing at St. Albans, in the county of Franklin and State 5 of Vermont, have invented certain new and useful Improvements in Carpet-Holding Frames, of which the following is a specification, reference being had therein to the accompanying drawings.

10 This invention relates to carpet-stretching frames for the purpose of holding carpets, rugs, and the like for cleaning or beating.

The invention consists in the construction and combination of mechanical elements 15 constituting the stretching and holding mechanism, substantially as hereinafter described and claimed.

Figure 1 is a perspective view of the entire stretching-frame and adjuncts with a carpet 20 or rug applied thereto. Fig. 2 is a side elevation of one of the corner-supports.

Let A represent a roller which is long enough to take on a carpet or rug of the desired length. To this roller loops or securing 25 devices B are attached at frequent intervals, and preferably such securing devices are longitudinally movable on the roller.

The character of the loops B is not very material, so that they afford opportunity for the 30 ready attachment of straps C. Hoops of thin metal or leather, with either hooked or perforated ends, will answer the purpose.

Straps C are somewhat longer than the width of the rug or carpet r which is to be cleaned. The straps are spread on the rug before it is taken up from the floor and secured by means of safety-pins p or other convenient attaching devices. The straps C are then hooked to the loops B, and the straps 35 and rug are rolled up about the roller A. Said roller A is easily detachable from the standards which support it while stretching the rug and from its crank and other accessories.

40 When the roller A (with the rug and straps rolled thereon) is taken to the place where the carpet is to be beaten, the journals on the roll A are applied to bearings in standards D D. These standards D D project from 45 bases E E and are suitably braced, as at F F.

Loops G on the bases of the standards are held by stakes H, which stakes are driven into the ground.

50 The ends of straps C not secured to the roller A are secured to the bar I by attachment to pins or buttons K thereon.

The bar K is held against rotation in upright standards D D. Clamps d d will serve to secure bar I to said standards.

The standards D D are rigidly held on 60 small trucks M, which trucks are provided with loops G, by which they may be staked down. This, however, is usually unnecessary, as braces O O are hinged to the standards D D, and the lower end of each of these 65 hinged braces rests on the ground.

Straps c c connect the hinged braces O O to the roller A and will wind up as the roller is wound.

When the carpet or rug r is spread on the 70 frame as in Fig. 1, that part next the roll A may be beaten or cleaned and then rolled up on the roller, said roller being held against backward movement by a pawl S on the standard D engaging a ratchet T on the 75 roller. The roller is turned by crank V. When it is desired to beat a part of the carpet or rug farther removed from the roller than can be easily reached, the first ends of the straps and carpet are wound on the roller A 80 and the roller is held by pawl S from giving back. The trucks M are of course moved along as the carpet is wound, being released for the purpose.

When the carpet is fully wound on roller A, 85 said roller can be released from its bearings and replaced "end for end." This will permit the carpet or rug to unroll and resume the position of Fig. 1, but turned over so as to present the reverse side for cleaning or beat- 90 ing.

It will be possible to ship the rug or carpet in convenient manner when rolled on roller A whether the bar I be present or not.

The draft on straps c c as the roller is 95 wound not only releases the braces O, but draws along the trucks. The braces O are prevented from swinging out too far by a cross-bar on m the truck M.

What I claim is—

1. A carpet stretching and holding machine consisting essentially of a pair of standards and means for holding them upright, a roller journaled in said standards, a pair of trucks, and a bar supported on said trucks, 105 and straps connecting said bar to the roller.

2. The combination, in a carpet-stretching machine, of a roller and movable attachments for securing a number of straps thereto in spaced relation, standards in which the 110 roller is journaled, a movable bar, straps connecting said bar to the strap-holding attach-

ments on the roller, bearings for the roller, and a ratchet and pawl operating on the roller to hold it against rotation.

3. In a carpet-stretching machine, a carpet-holding roller suitably journaled, straps extending from said roller, a bar to which said straps are attached, and trucks, supporting said bar, all combined.

4. In a carpet - stretching machine, the combination of a roller suitably supported in bearings, straps extending from said roller, a bar sustaining the ends of the straps remote

from the roller, trucks provided with standards on which the bar is supported, braces hinged to said standards and extending ¹⁵ down at the front part of the trucks, and straps connected to the roller and said braces, as set forth.

In testimony whereof I affix my signature in presence of two witnesses.

GEORGE W. STICKLE.
